UNITED STATES PATENT OFFICE.

STANLEY W. FINCH, OF WASHINGTON, DISTRICT OF COLUMBIA:

COMBINATION TOOL.

Application filed July 18, 1924. Serial No. 726,780.

To all whom it may concern:

Be it known that I, STANLEY W. FINCH, a citizen of the United States, residing at Washington, in the District of Columbia, 5 have invented certain new and useful Improvements in Combination Tools, of which the following is a specification.

This invention pertains to a combination tool, and more particularly, that type of 10 tool employed for opening up petcocks on Ford automobiles.

As will be appreciated by those skilled in the art, the petcocks attached to the sump of the Ford car are located at a point where 15 they are relatively inaccessible, and it has been the common practice to provide a tool for manipulating the petcocks. This invention pertains to a tool of that type and has for its main object the production of a 20 simple structure through the use of which the petcock may be readily engaged and turned on and off, and in addition to this, it has the added feature of providing means whereby the opening through the petcock, 25 when it is open, may be readily cleared out in case it should become stopped up.

The structure is shown in the annexed drawings, wherein,—

Fig. 1 is a perspective view of the tool; 30 Fig. 2 a side view thereof with the handle portion broken away;

Fig. 3 a similar view as seen at right angles to that disclosed in Fig. 2, and

Figs. 4 and 5 perspective views respectively of certain modified forms of the structure.

The tool is produced from a single piece of wire bent to form.

Referring first to Figs. 1 to 3, which disclose the preferred embodiment of my invention, the tool may be said to comprise a body 1 having a loop or handle 2 at one end while at its opposite end it is provided with a pair of jaws and a cleaning finger. To produce the jaws and finger, the wire is 40 initially bent back upon itself and then formed into a hook-shaped member, thus producing two eyes or loops 3 and 4 connected together by the bent section 5. Said eyes or loops stand in spaced relation to each 45 other and form a recess denoted in Fig. 2 by 6, for the reception of the finger piece of the valve element of the petcock. Owing to the connection of the loop by the member 5, a certain amount of resiliency is present 50 therein and there is thus produced two parallel jaws (the loops) which may be readily

forced into engagement with the finger piece of the petcock, and which will, owing to the resiliency of the structure, grasp and maintain their position upon such element. 60

The wire extends outwardly from the loop 4 and to the rear thereof, as at 7, and is then bent outwardly at right angles to form an outwardly projecting finger 8, which finger may be utilized after the petcock is 65 turned on, to clear out the petcock and the opening in which it is mounted. This clearing finger 8 will be located at a point sufficiently distant from the loops or jaws 3 and 4 that when said jaws are in engagement with the handle of the petcock, the tool may be turned to open the petcock without fear of the finger 8 contacting the outer wall of the sump, which, as will be readily appreciated by those familiar with the Ford 70 car, is inclined, and by reason of such inclination would prevent the proper turning of the tool if the finger were located too close to the loops or jaws.

While I prefer the embodiment above described, it will be readily appreciated that the structure may be somewhat modified and two such modifications are shown in Figs. 4 and 5.

In Fig. 4, instead of forming the jaws 85 in the form of loops or eyes, the wire is first bent back upon itself and then the extreme forward bent portion is turned at right angles to the body 1, forming a pair of jaws 9 and 10, the wire of the upper jaw extending rearwardly as at 7^a in substantial alignment with the body 1 and then being turned outwardly to produce a clearing finger 8^a. 90

In Fig. 5, the initial bend is formed at a point more remote from the connecting 95 member 5^a, after which the second bend is formed, the structure being substantially the same under this arrangement as that shown in Figs. 1 to 3, with the exception that instead of being formed upon a curve, the 100 end is bent substantially at right angles at two different points. Two jaws 11 and 12 are thus produced. As in the other structures, the clean-out finger is provided, and in this instance is denoted by 8^b. 105

It will be appreciated that the structure is at once light and simple, may be readily formed, and is easy of manipulation both in placement with reference to the petcock for the purpose of opening the same, and for 110 positioning the finger 8, (8^a or 8^b) when it is desired to clean out the petcock.

What I claim is:

1. A tool for the purpose described formed from a single metal rod bent at one end to form two substantially parallel looped or hook-shaped members.
2. As a new article of manufacture, a tool for the purpose described formed from a single piece of wire, said wire being doubled upon itself with such double portion bent into the shape of a hook, thereby producing two loop-shaped members lying in spaced relation to each other.
3. As a new article of manufacture, a tool for the purpose described formed from a single piece of wire bent to form, the wire being bent back upon itself and then shaped into a hook, thereby producing two loop-shaped members in spaced relation to each other, the free end of the wire extending from one of the loop-shaped members to produce a clearing finger.
4. As a new article of manufacture, a tool for the purpose described formed from a single piece of wire, said wire being bent to produce a pair of spaced jaws with a wire extending rearwardly from one of said jaws

and then outwardly at right angles to form a clearing finger.

5. As a new article of manufacture, a tool for the purpose described formed from a single piece of wire, said wire at one end being fashioned into a handle and at its opposite end being doubled upon itself, the extreme outer portion of the double section being bent into the shape of a hook thereby producing a pair of loops lying in spaced relation to each other, the wire from one of said loops being extended rearwardly therefrom and then outwardly at right angles to the axis of the tool, thereby producing a finger.

6. A tool for the purpose described formed from a single piece of wire bent to form, and having at one end engaging jaws consisting of substantially parallel sections of said single piece of wire, the end of one of said sections extending rearwardly and then outwardly at substantially a right angle to form a clearing finger.

In testimony whereof I have signed my name to this specification.

STANLEY W. FINCH.
